Martin Jochimson.

UNITED STATES PATENT OFFICE

JOSEPH DOEPLER, OF NEW YORK, N. Y.

REVOLVING MERCURY FLASHER

Application filed June 16, 1927. Serial No. 199,265.

This invention relates to improvements in electric switching devices of the rotary type and particularly to that class of these devices which are used to light and extinguish periodically electric lamps or groups of lamps. Such switches are principally used to produce lighting effects of electric signs and are generally known as "flashers."

It is the object of this invention to provide a flasher-mechanism in which all the circuit making and breaking contacts are completely enclosed in a single cylindrical chamber and protected thereby.

It is another object of the invention to provide a flasher in which mercury forms the contact making medium.

It is a further object of the invention to provide a flasher in which the same mechanism can be varied for a plurality of switching conditions as required for "spelling" flashers or for those of the "running border" type.

It is also an object of the invention to provide a flasher which is very simple in construction and embodies a small number of parts.

With these and other objects in view which will become more apparent as the description progresses, the invention consists in a novel construction and arrangements of parts hereinafter more fully described and finally pointed out in the appended claims.

In the drawings which form a material part of the specifications,

Fig. 1 is a front elevation of my flasher partly in section on line 1—1 of Fig. 2.

Fig. 2 is an end elevation seen in the direction of arrows 2—2 of Fig. 1. Parts of the casing 14 are broken away to show the interior.

Fig. 3 is a part top plan of Fig. 1 as indicated by arrows 3—3 at that figure.

Fig. 4 is part of a side view as indicated by line 4—4 at Fig. 2.

Fig. 5 is a front elevation showing a preferred arrangement of variable contact segments.

Fig. 6 is a side elevation of Fig. 5 showing the mounting of the segments partly in section.

Fig. 7 is a front elevation of a single contact segment.

This flasher consists of a central horizontal shaft 11 mounted in suitable journals 12 which are held on bearing blocks 13 and mounted on a base plate 10 preferably of insulating material. On this shaft a cylindrical casing is supported to rotate therewith which consists of a tube of insulating material 14, preferably made of glass. It is held between end plates 15 likewise of insulating material. The ends of shaft 11 which extend beyond journals 12 are used to connect the tube to a rotating medium as an electric motor by means of a pulley, clutch, or other driving medium. Within the drum formed by tube 14 and end disks 15 a plurality of insulating bushings 16 are carried on shaft 11. These bushings are provided with a cylindrical recess 16^a at one end and a cylindrical collar 16^b at the other end so that the collar 16^b of each bushing enters into the recess 16^a of the adjacent one (see Figs. 1 and 6). Between each two bushings one or more contact plates 17 are held on collar 16^b thereof. These plates (see Fig. 7) consist of a ring 17^a and disk-segment 17 integral therewith, preferably made from sheet metal. Bushings 16 are provided with a plurality of longitudinal apertures of which the illustrations show three. These apertures are close to the shaft 11 so that they come within the diameter of collars 16^b and recesses 16^a. A wire conductor 25 is located in each one of these apertures, one end of each conductor is soldered to a different segment 17. These reach through registering apertures in end plates 15 to the outside of these plates and are fastened to them by means of long radial screws 18 which serve as conductors and lead beyond the periphery of plates 15.

On the outside of tube 14 are mounted longitudinally thereof rectangular bars 19 which extend beyond both end plates 15 and accommodate the outer end portions of screws 18 near both ends. Each bar is provided on its outer face with a slot 20 extending from each end an equal distance towards its center, but these slots are of a different length for each bar 19. The bars 19 are encircled by

collector rings 21 corresponding in number to the number of contact plates within the tube 14. Each ring 21 is placed in alignment with one of the contact plates. A strip conductor 22 rests on the bottom of each slot 20 and is fastened at one end to screw 18 by means of a nut 24 and at its other end to a collector ring 21 by means of a screw 23. Slots 20 are deep enough in bars 19 to leave a space between rings 21 and conductor 22 which is occupied by an insulating cover.

In the manner described an insulated path is provided from each segment inside of the tube 14 to a collector ring in alignment therewith on the outside thereof. For instance in Fig. 1 the conductor 25 is shown attached to the first contact plate 17 nearest the end plate 15. This conductor leads to the point of screw 18 which leads to flat conductor 22 and therefrom through screw 23 to the first collector ring 21. The same bar 19 provides in a like manner for the connection of the first disk and collector ring at the opposite end of tube 14. The second pair of contact plates 25 is connected to the second pair of collector rings from end plates 15 by conductors 25 occupying apertures in bushings 16 which are 120 degrees distant from the former, and their screws 18 and bars 19 occupy corresponding positions on tube 14. The strip conductors 22 in slot 20 for this pair of contact plates pass insulated below the first collector ring to the second one.

Fig. 4 shows this connection for a collector ring in third position from end disk 15.

In contact with each collector ring is a carbon brush 30 mounted in holder 31 upon an insulator bar 32 and supported on posts 33 which are joined to bearing blocks 13. A binding screw 34 on each brush holder 31 provides a terminal for a line wire.

Into tube 14 a small quantity of mercury 35 is poured through an inlet opening in end disk 15 closed by a screw 27. This mercury 35 covers a small arc of the tube cylinder 14 at its bottom line and remains there by gravity in shape of a bar extending from one end plate to the other, while the casing is rotated. One of the contact plates is preferably a complete disk while the others are segments of different arcs to suit the conditions required for the performance of the flasher. A plurality of contact disks 17 shown in Fig. 7 can be so placed on the collars 16^a of bushings 16 that several openings, varying in degrees can be left between the segments without making special segments of the desired arcs. By tying the nuts 26 on shaft 11 outside of end plates 15 these plates and all bushings 16, and contact plates 17 are pressed against each other on tube 14 and the segments forming the contact plates are clamped in their selected position.

In the operation of this device current enters through one of the carbon brushes 30 into

the collector ring in contact therewith, passes through screw 23, strip conductor 22, screw 18 and wire 25 into the contact plate 17 connected thereto. As one of these plates is a circular disk it passes into the mercury there-through at all times. In case another plate 17 is passing through the mercury at that instant it passes through the same and in the above described path to the collector ring and carbon brush of that contact plate completing the circuit. If the casing is rotated the various segmental contact plates make and break contacts in desired manner in accordance with their arrangement on bushings 16 and shaft 11 and with the degrees of their arcs of contact.

This flasher has the advantage that no hard metallic contacts are broken, that no open arcs are formed and that a greater number of combinations may be made and that the length of contact time may be varied without mechanical alterations of the same instrument.

Another great advantage of this flasher is its noiselessness.

Having thus described my invention, what I claim as new and desire to secure by Letters Patent is:

1. In a switching device a cylinder of insulating material, an insulating casing enclosing said cylinder, means mounting said casing and said cylinder for rotation on a common horizontal axis, a plurality of segmental disks on said cylinder and a flowable liquid conductor at the bottom of said casing, each disk consisting of one or more spaced segments providing means to make and hold contacts with said liquid conductor according to the lengths of their segmental arcs and to break said contacts according to the lengths of the spaces between said segments when said casing is rotated.

2. In a switching device a tubular casing closed at its ends, an insulating shaft within said casing, means mounting said casing and said shaft for rotation upon their common axis, a liquid conductor at the bottom of said casing, a plurality of disks mounted on said shaft in parallel planes, each disk being divided into segments of different arc lengths, comprising means to make contacts of different duration with said liquid conductor during each revolution of said disks, and means on said shaft for conducting current from each disk to the outside of said casing.

3. In a switching device a tube of insulating material, a pair of end plates closing said tube comprising a casing, a shaft forming the axis of said casing, means mounting said shaft and said casing rotatably in horizontal position, a liquid conductor at the bottom of said casing, a plurality of disk segments held on said shaft held insulated from each other in parallel planes, said liquid conductor forming means to make contacts of different dura-

- tion between segments in different planes, and a plurality of conductors on said shaft each conductor leading from segments in the same plane to one of said end plates.
5. In a switching device a tube of insulating material, end plates closing the openings of said tube forming a casing, a shaft forming the axis of said casing mounting it rotatably in horizontal position, mercury covering the bottom line of said casing, a plurality of disk-segments fastened to said shaft but insulated therefrom, a conductor extending from each segment to one of said end plates, and radial conductors on said end plates to 15 their periphery.
5. In a switching device a tubular insulating casing closed by plates at its ends, means mounting said casing rotatably on a horizontal axis, mercury within said casing and 20 a pair of segmental disks in said casing held to rotate with the same adapted to form a connection between said plates through said mercury, and a conductor on each segmental disk, said conductors connecting each disk to a different end plate and to the periphery thereof.
6. In a switching device a tubular insulating casing, a shaft mounting said casing rotatably on its axis, a plurality of disks on said shaft, each disk being divided into spaced 30 segments mounted to rotate with said casing, mercury in said casing, a collector ring for each disk outside of said casing, and a conductor leading from each disk to one of said collector rings forming means to close a circuit between two collector rings.
7. In a switching device an insulating casing, a pair of contact plates arranged in parallel planes within said casing, means mounting said plates and said casing for rotation 40 upon a common axis, a collector ring for each contact plate outside of said casing, a liquid conductor at the bottom line of said casing adapted to establish during each revolution of said casing a plurality of connections of differing duration between said contact plates, and conductors leading through opposite ends of said casing for connecting each contact plate with its collector ring.
8. In a switching device an insulating casing having end plates closing opposite sides thereof, a shaft mounting said casing for rotation and passing through said end plates, a plurality of shouldered bushings on said shaft within said casing, a disk having radial 55 slots on the shoulder of each bushing, mercury in said casing adapted to close a circuit between two of said disks and conductors in the body of each bushing leading to the outside of said casing.
- 60 9. In a switching device a tubular insulating casing, a shaft extending therethrough, a plurality of contact plates mounted on said shaft insulated from each other, a plurality of insulator bars on the outside of said casing, parallel to said shaft, collector rings held
- on said insulator bars, brushes in contact with said rings and conductors leading to opposite ends of said bars and to said contact plates, connecting each contact plate to one of said brushes.
10. In a contact timing device an insulating casing having parallel end plates, a shaft extending longitudinally through said casing a plurality of insulating bushings covering said shaft within said casing, each bushing having a projecting shoulder at one end and a recess formed at the other end, the shoulder of one bushing fitting into the recess of the adjacent bushing, a contact plate mounted on the shoulder of each bushing, a longitudinal aperture eccentrically located in each bushing, and a conductor leading from said contact plate through the eccentric aperture in the adjacent bushing to one of said end plates.
11. In a switching device a tubular insulating casing, having closed opposite ends, collector rings surrounding said casing, a shaft of insulating material extending longitudinally through said casing, contact plates mounted on said shaft in parallel planes, a liquid conductor within said casing each contact plate having a conductor thereon which leads along said shaft to one end of said casing, thence radially to the periphery thereof and to one of said collector rings.
12. In a switching device a tubular casing, an insulating shaft therein, segmental contact plates on said shaft, each plate having a central aperture accommodating said shaft, conductor channels within said shaft disposed eccentrically around its axis parallel thereto, and a conductor for each contact plate occupying a different conductor channel and passing through the aperture of the adjacent contact plate.
13. In a switching device a tubular casing, an insulating shaft surrounding the axis of said casing, a plurality of contact plates held on said shaft, each contact plate consisting of a plurality of disk segments, each segment being rotatably held in a groove of said shaft, and means to press the flat sides of said segments against each other to lock them in selected position.
14. In a contact timing device an insulating drum shaped receptacle, a shaft extending longitudinally through said receptacle mounting it for rotation on its axis, a plurality of bushings longitudinally adjacent to each other covering said shaft, each bushing having a shoulder projecting from one of its ends and a plurality of disk segments rotatably mounted on said shoulder and means to hold said segments in selected positions around said shaft for forming arcs and openings of different degrees in their common circumference.
15. In a contact timing device an insulating casing, a shaft extending through said casing mounting it for rotation on its axis, a

liquid conductor in said casing, a plurality of bushings covering said shaft, each bushing having a shoulder on one of its ends and a recess in its other end, the shoulder on one bushing fitting into the recess of the adjacent bushing, a plurality of disk segments held rotatably on each shoulder, means to press said bushings against each other for clamping said segments between them in selected positions around said shaft providing means to adjust the time of open and closed contact between each segment on the same shoulder and said liquid conductor.

In testimony whereof, I JOSEPH DOEPPLER, signed my name to this specification this 4th day of June, 1927.

JOSEPH DOEPPLER.
